UNITED STATES PATENT OFFICE.

JOSHUA H. GRIFFITH, OF ELLIS, KANSAS.

GAS-GENERATING BURNER.

1,156,139.

Specification of Letters Patent.

Patented Oct. 12, 1915.

Application filed February 2, 1915. Serial No. 5,784.

To all whom it may concern:

Be it known that I, JOSHUA H. GRIFFITH, a citizen of the United States of America, residing at Ellis, in the county of Ellis and

5 State of Kansas, have invented certain new and useful Improvements in Gas-Generating Burners, of which the following is a specification, reference being had therein to the accompanying drawing.

10 This invention relates to gas generating burners and has for its principal object the production of a burner which may be placed within the fire box of a stove in such a manner as to allow the burner to easily heat the 15 desired portions of the stove when the same is in operation.

Another object of this invention is the production of a gas generating burner which is so formed as to easily vaporize the 20 oil so that upon the mixing of the vaporized oil with the air, a gas will be produced which is adapted to be ignited upon passing from the interior of the burner.

Another object of this invention is the 25 production of a gas generating burner having a simple and efficient means for regulating the amount of vaporized oil which is adapted to be admitted to the mixing chamber whereby the amount of gas produced 30 may be increased or diminished as desired.

A still further object of this invention is the production of a gas generating burner having a plurality of burner pipes extending 35 from its gas chamber whereby the burner pipes may extend to desired positions within a stove so that the various portions of the stove may be heated as desired.

With these and other objects in view, this 40 invention consists of certain novel combinations, constructions, and arrangements of parts as will be hereinafter fully described and claimed.

In the accompanying drawings:—Figure 1 is a detailed perspective view of the gas 45 generating burner. Fig. 2 is a central longitudinal section through the burner. Fig. 3 is a top plan view of the device. Fig. 4 is a horizontal longitudinal section through the device, taken below the central partition. Fig. 5 is an end elevation of the burner. Fig. 6 is a section taken on the line 6—6 of 50 Fig. 2. Fig. 7 is a section taken on the line 7—7 of Fig. 2. Fig. 8 is a fragmentary sectional view of a portion of the device illustrating the manner in which the valve member is carried. Fig. 9 is a detailed perspec-

tive view of the valve stem. Fig. 10 is a fragmentary detailed perspective view of the upper portion of the burner, showing the gas pipes extending therefrom.

Referring to the accompanying drawings by numerals it will be seen that 1 indicates the body of the burner which is preferably cylindrical in shape but which may be so constructed as to embody any desired shape 60 or formation. This body 1 comprises a casing which is hollow and has one end thereof closed by the head 2 and the opposite end thereof closed by the head 3. The head 3 is provided with a plurality of openings 4 thereby forming the stays 4'. It will be seen that by providing the openings 4, air may be admitted into the interior of the casing 1 as the occasion requires. A partition 5 is fixedly secured within the interior of 70 the casing 1 adjacent its central portion so as to extend in a horizontal plane as will be seen by referring to Fig. 2. This partition 5 has an integral wall 6 formed upon one end thereof, which wall 6 extends at right 75 angles to the partition 5 so as to be connected to the inner upper portions of the casing 1 thereby forming a tight closure at one end of the partition 5. The opposite end of this partition 5 however terminates 80 at a spaced distance from the end 2 as indicated at 3' in Fig. 2 for the purpose of allowing the gas formed in the mixing chamber 8 to pass around this end of the partition. A number of apertures 7 are formed in the 85 casing 1 for the purpose of allowing the gas carried within the gas chamber 8 to escape from the interior of the burner and to be easily ignited as the same passes through the apertures 7. A pipe 9 is carried upon 90 the upper portions of the casing 1 so as to extend around the apertures 7 as clearly shown in Figs. 1 and 3. This pipe 9 is fixedly retained in position upon the casing by means of the clips 10 which embrace the 100 pipes and are fixedly secured upon the upper portions of the casing in any suitable manner. It will be seen that as the oil passes through the pipe 9 the heat from the flames caused by the burning of the gas passing 105 through the apertures 7 will heat the pipes and cause the oil to be vaporized before it reaches the mixing chamber. This pipe 9 is provided with an elongated depending neck 110 13 which communicates with the valve casing 14 by means of the neck 14'. This neck 13 extends upwardly to communicate with

the valve casing 14 within the air chamber 11. The valve casing 14 extends entirely through the air chamber 11 and communicates with the interior of the mixing chamber 12. In order to retain this valve casing in its correct position one end thereof is carried by the thickened portion of the head 3 while the central standard 16 is adapted to be positioned upon the valve casing for the purpose of supporting the inner end thereof. This standard 16 extends in a vertical position so as to bear against the vertical wall 6 of the partition 5. The valve member 21 is provided with a gripping portion 22 which may be easily gripped so as to actuate the valve member 21 as the occasion requires. A threaded portion 23 is formed upon the valve member 21 and this threaded portion 23 is adapted to pass through the threaded opening 24 formed in the thickened portion 15 of the head 3. It will be seen that the valve member 21 extends throughout the entire length of the casing 14 so as to pass from the inner portions of the casing as clearly shown in Fig. 2. Since the casing 14 tapers toward its inner end the inner end of the valve member 21 will become wedged as shown at 21' in Fig. 2 for the purpose of cutting off the supply of vaporized oil when it is so desired.

When the device is in operation air will pass through the openings 4 formed in the head 3 and into the air chamber 11. The air may then pass downwardly into the mixing chamber 12 under the partition 5. The gripping portion 22 may then be actuated so as to move the valve member 21 and allow oil to pass into the mixing chamber 12. As the oil and air mix, a gas will be formed which will pass around the end of the partition 5 and will pass into the gas chamber 8. As the gas passes from the chamber 8 through the apertures 7 it may ignite so as to allow the flames to heat any desired article or receptacle or to heat a stove within which the burner is positioned. As the flames heat the pipe 9 the oil therein will be vaporized so that upon passing through the neck 13 into the casing 14 it may be discharged in a vaporized condition from the casing 14 into the mixing chamber thereby reducing the cost of producing the gas and causing the burner to operate more efficiently. It will of course be seen that the draft of the air caused by the passage of the air into the chamber 11 through the openings 4 will cause the gas formed in the mixing chamber to quickly pass into the gas chamber 8 thereby preventing a backfire in the mixing chamber 12.

It will be seen that the casing 1 is adapted to carry a nipple 25 communicating with the interior of the gas chamber 8. The gas pipe 26 may be held in engagement with the

nipple 25 by means of the collar 27. From this pipe 26, burner pipes 28 may extend and the admission of gas to these pipes 28 may be regulated by the valves 29. It will be seen that the gas from the chamber 8 will pass through the nipple 25 and into the pipe 26. As the various valves 29 are actuated the gas will pass into the different burner pipes 28 and will be discharged through the burner openings 30. These openings may be provided with a blaze deflector 31 supported upon the frame 32 so as to cause the blaze made by the igniting of the gas passing from the burner openings to be spread or deflected. It is obvious that the pipes 26 and 28 may extend in any desired shape or to any desired position so as to efficiently heat the several portions of a stove within which the burner is adapted to be positioned.

From the foregoing description it will be seen that a very efficient gas generating burner has been produced which is so formed as to be easily carried within a stove for heating the stove and which has its several parts so arranged as to readily vaporize the oil before the oil is passed to the mixing chamber whereby a very pure gas may be very quickly and cheaply produced when the burner is in operation. It will also be seen that the valve operating mechanism is so formed as to easily control the supply of vaporized oil to the mixing chamber, this valve operating mechanism being easily supported in a convenient position to be operated.

It will be seen that the casing 14 extends for a considerable distance into the mixing chamber and owing to the fact that the cooling chamber is formed adjacent one end of this mixing chamber, the point within the mixing chamber whereat the vaporized oil is admitted is far enough from the open end of the generating burner to prevent the igniting of the vaporized oil by the flames without the burner. Therefore, it will be seen that the clogging of the mixing chamber by the formation of the soot therein is prevented and consequently the burner will be clean within its inner portions at all times so as to allow the gas to be easily generated.

What I claim is:—

1. In a gas generating burner of the class described, the combination of a casing, a central partition carried within said casing, forming a mixing chamber and a gas chamber, said partition provided with an integral vertical wall extending at right angles thereto forming an air chamber, said partition terminating at a spaced distance from one end of said casing to communicate said mixing and gas chambers, and means for supplying said mixing chamber with vaporized oil, said air chamber having openings to the outside air and communicating with said mixing chamber whereby air is supplied

to the mixing chamber, said gas chamber having openings for the exit of gas to be burned.

2. In a gas generating burner of the class described, the combination of a casing, said casing provided with a closed end, a head carried by the opposite end of said casing and provided with a plurality of openings for allowing the air to be admitted into the interior of said casing, a partition carried within the central portion of said casing and extending in a horizontal plane, said partition provided with a vertical wall at one end, the opposite end of said partition terminating at a spaced distance from the closed end of said casing, said partition forming a mixing chamber therebelow and a gas chamber thereabove, said casing provided with a plurality of apertures communicating with the interior of said gas chamber, an air chamber formed at one end of said casing and communicating with said mixing chamber, means for supplying said mixing chamber with vaporized oil whereby the air from said air chamber may pass into the mixing chamber and be mixed with the vaporized oil for producing a gas whereby the gas may pass upwardly into said gas chamber and be expelled therefrom through said apertures when the device is in operation.

3. In a gas generating burner of the class

described, the combination of a casing, said casing provided with a gas chamber and a mixing chamber, said chambers communicating with each other, said casing also provided with an air chamber communicating with said mixing chamber, a tapering valve casing carried within said air chamber and extending into said mixing chamber, a rotatable valve member carried within said valve casing, said valve member being adapted to open and close said valve casing, an oil pipe carried upon the upper portions of said casing, said casing being provided with a plurality of apertures communicating with said gas chamber, whereby the flames caused by the burning of the gas passing from said casing will vaporize the oil within said pipe, said pipe provided with a depending neck and communicating with said valve casing, said valve member being adapted to regulate the supply of vaporized oil passing into the mixing chamber whereby the mixing of the air and vaporized oil within the mixing chamber will form a gas which may pass into said gas chamber so as to be exhausted therefrom and be ignited.

In testimony whereof I hereunto affix my signature in presence of two witnesses.

JOSHUA H. GRIFFITH.
